UNITED STATES PATENT OFFICE.

JOHN H. BURKHOLDER, OF ASHLAND, OHIO.

DESIGN FOR A DOOR-HANGER HASP.

SPECIFICATION forming part of Design No. 34,445, dated April 30, 1901.

Application filed March 18, 1901. Serial No. 51,792. Term of patent 7 years.

To all whom it may concern:

Be it known that I, JOHN H. BURKHOLDER, a citizen of the United States, residing at Ashland, in the county of Ashland and State of Ohio, have invented and produced a new and useful Design for Door-Hanger Hasps, of which the following is a specification.

My invention relates to a new and useful design for door-hanger hasps; and it consists of a metallic plate of the configuration and ornamentation shown in the accompanying drawing, in which the figure is a perspective view.

The leading feature of my invention consists of a substantially U-shaped metallic plate A, the free ends of the limbs B and C being slightly curved. On the limb B there are provided circular apertures b and b' and on the limb C the square apertures c and c'.

In the upper portion of the hasp there is formed the oblong slot D, the ends thereof being slightly curved, and upon either side of the middle of the slotted aperture D are provided the curved projections E and F.

These hasps are sold to the trade and are used in conjunction with door-hanger pulley frames and pulleys adapted to be journaled or hinged to the hasp.

What I claim is—

The design for a door-hanger hasp herein shown and described.

In testimony whereof I have hereunto set my hand in the presence of two subscribing witnesses.

JOHN H. BURKHOLDER.
